GEORGE DORFFEL, OF OAKLAND, CALIFORNIA.

PUMP.

1,210,152.

Specification of Letters Patent. Patented Dec. 26, 1916.

Application filed March 30, 1916. Serial No. 87,716.

To all whom it may concern:

Be it known that I, GEORGE DORFFEL, a citizen of the United States, and a resident of Oakland, in the county of Alameda and State of California, have invented a new and Improved Pump, of which the following is a full, clear, and exact description.

This invention relates to pumps and particularly to an improved arrangement of pump which elevates water or other liquid through the use of compressed air.

An object in view is to provide a new construction and arrangement of parts in a pump which will utilize compressed air as a motive power in such a way that the pump will be automatically operated continuously as long as the water is permitted to flow or the air turned on.

A still further object of the invention is to provide an improved arrangement of water pump for utilizing compressed air as the propelling medium, the parts being so arranged that the expenditure of air will be reduced to a minimum.

In carrying out the objects of the invention a pair of tubular members are provided formed with apertures in the lower part thereof for the admission of water. These members or tubes are adapted to be entirely or almost entirely submerged so that a float in each of the tubes will be raised by the water entering therein under certain circumstances. The various floats used in this device act as valves when lowered and coact with outlet valves so that during the operation of the pump water may freely enter and move the float upwardly and the water be allowed to escape through the outlet valve when air is forced above the water. This arrangement of float and valve mechanism beneath the water coacts with a valve operating mechanism above the water which turns the air on and off automatically so that the various tubes will operate successively.

In the accompanying drawings:—Figure 1 is a side view of the air controlling valve and associated parts, the operating tanks and associated parts being shown in section for better illustrating the construction.

Fig. 2 is a side view on a somewhat enlarged scale of the tubular members or pipes arranged in the well. Fig. 3 is a transverse fragmentary horizontal section through Fig. 1 on line 3—3. Fig. 4 is a top plan view of a rotating valve member shown in Fig. 3, the same being on an enlarged scale, Fig.

5 is an edge view of the valve member shown in Fig. 4, the same being taken on line 5—5 of said figure. Fig. 6 is another edge view of the valve shown in Fig. 4, the same being 60 taken on line 6—6 of said figure.

Referring to the accompanying drawings by numerals, 1 indicates a well containing water 2 in which the tubular members or pipes 3 and 4 are submerged or partially submerged. As both pipes 3 and 4 are of identical construction a description of one will be sufficient for both. Pipe 4 may be made into sections and connected together by suitable tubular members threaded together as shown in Fig. 2, the upper part of the pipe being provided with a cap 5 to which an air tube 6 is connected so that air may be introduced into the top of the pipe whenever necessary, as hereinafter fully described. The bottom of the pipe is preferably provided with a cap 7 but a bottom section or portion of the pipe is formed with a plurality of apertures 8 through which the water may freely pass and from thence upwardly through the spider 9 and the valve seat 10, a valve member 11 being normally unseated by the spring 12. Spring 12 is preferably a comparatively weak spring and is intended to raise the valve 10 slightly off 85 its seat when the pressure on opposite sides of the valve is equalized.

Immediately above the valve 11 is an outlet elbow 13 to which a pipe 14 is connected by being threaded thereto or secured in any suitable way. The pipe 14 has a casing 15 connected therewith which casing has a valve 16 arranged therein adapted to coact with the seat 17. Valve 16 is normally held closed by a spring 18 acting against the enlargement 19 and against the spider 20. To the upper end of the casing 15 is connected a pipe 21, which pipe in turn is connected to a fitting 22 discharging into an outlet pipe 23, which outlet pipe may direct the water to a storage tank or to any other place preferred. Pipe 3 is provided with a valve 24 and other parts similar to valve 16 and associated parts so that water may be discharged at one time past valve 16 and at another time past 105 valve 24, whereby a substantially continuous stream is supplied to the outlet pipe 23.

Arranged in the pipe 4 a short distance above the elbow 13 is a ring 25 into which a tubular member 26 is fitted, said tubular member having connected therewith a plurality of uprights 27 forming guides for the

float 28 which is preferably formed of wood. A connecting member or cap 29 is secured to the upper ends of members 27 for limiting the upward movement of the float. The tubular member 26 is provided at its upper end with a smooth portion 30 acting as a valve seat against which the washer 31 secured to the float 28 presses when the float is in its lowered position, as shown in dotted lines in Fig. 2.

In operation, when air under pressure is allowed to pass through pipe 6 into the upper part of pipe 4, as shown by the arrow, the water in the upper part of pipe 4 will be forced downwardly, the first movement causing valve member 11 to seat and a continued movement causing part of the water to pass upwardly through elbow 13 and finally out past the valve member 16. The water will continue to flow until the float 28 has become seated on member 26. At this time the air will be shut off from pipe 6 by mechanism hereinafter fully described and turned on to pipe 32 so that the moving parts in pipe 3 may operate in a similar manner to the parts just described for forcing water past valve 34. As soon as the air has been shut off from pipe 6 and said pipe has been exhausted to the atmosphere or some other place so as to relieve the pressure in pipe 4, the pressure or tension of the water above and below the valve member 11 will become equal and, consequently, valve member 11 will become unseated so that the head of water in the well will cause some of the water to flow through apertures 8 and reestablish the head of water in the pipe 4. This, of course, will raise the float 28 to its highest position. After the parts in the pipe 3 have operated for causing a discharge of the water the air will be turned off from said pipe and again switched on to pipe 4 so that the cycle will be repeated. In fact, this cycle is repeated continuously as long as the air is being turned on and off by the mechanism hereinafter fully described.

Referring more particularly to Fig. 1, a mechanism will be seen which is intended to turn on and off the air so as to operate the parts shown in Fig. 2, this mechanism being designed to be mounted at the top of the well or at any other convenient point. Air under pressure is designed to be supplied to the feed pipe 33, said air being provided by an air pump or by a tank filled with compressed air, the same forming no part of the present invention. If desired, a valve may be arranged in pipe 33 for turning the air on and off whenever desired, but if said valve is not turned off the pump may be stopped by shutting off the water and again automatically caused to operate by merely turning the water on again. The pipe 33 is connected with a

casing 34, as more clearly shown in Fig. 3, so that the compressed air may pass through the inlet port 35 into the cut away portion 36 of the valve member 37. Valve member 37 is not only provided with the cut away portion 36 but with a passageway 42 and with exhaust ports 38 and 39. Exhaust ports 38 and 39 are designed to exhaust into the exhaust passageways 40 and 41, respectively. When the valve is in the position shown in Fig. 3 the air will pass into the valve and therethrough so as to supply the upper end of pipe 32 with compressed air, which air will pass downwardly into pipe 3 as heretofore described. When the valve member 37 is in the position shown in Fig. 3 air is being supplied to pipe 32 and pipe 6 is exhausting through the exhaust passageway 38 in the valve and through the passageway 40 to the atmosphere. If the valve should be turned until passageway 42 registers with the pipe 6, pipe 32 would exhaust through the exhaust passageway 41 and compressed air would be supplied to pipe 6 for operating the parts in pipe 4 as heretofore described.

In order to provide means for automatically moving the valve member 37 back and forth and for alternately supplying compressed air to pipe 6 and pipe 32 and alternately exhausting said pipes, the buckets or tanks 43 and 44 (Fig. 1) have been provided together with the parts connected thereto. These buckets are pivotally mounted at 45 and 46, respectively, to a lever or walking beam 47 pivotally mounted at 48 on the standard or support 49, which standard or support is provided with a base 50 held in position by any desired means. The walking beam 47 is provided with uprights 51 and 52, which uprights have apertured extensions 53 and 54 to which cables or ropes 55 and 56 are secured, said cables or ropes being in turn secured at 59 and 60 to the cable or rope 61. The cable or rope 61 is secured substantially midway between the ends to the grip 62 of the handle or lever 63 rigidly secured to the stem 64 of the valve member 37, while the ends of this cable or rope are secured to the sliding plates 65 and 66 loosely mounted on bar 67. Bar 67 is connected with the uprights 51 and 52 and consequently rocks therewith. A weight 68 is slidably mounted on the bar 67 and is designed to assist the weight of the buckets or tanks 43 and 44 and in turn the valve member 37. The springs 69 and 70 are provided for cushioning the blow of this weight.

The tanks 43 and 44 are intended to accommodate water or other liquid which is usually sufficient to almost fill only one tank. When the air is turned on to the pipe 32, as shown in Fig. 3, air will not only pass down pipe 32 into pipe 3 but will also

pass into a by-pass or pipe 71, which by-pass or pipe has a valve 72 connected therewith, which valve in turn is connected through the flexible hose 73 to the inlet pipe 74 and tank 43. A distributing head 75 is provided which is perforated and if desired supplied with a small quantity of cotton or other waste 76 for preventing the passing of water through this pipe. As 5 the main supply of air enters the pipe 3 to force water therethrough a reduced supply will at the same time be forced into tank 43 and consequently will force the water therefrom through the pipe 76 and flexible 10 tube 77 to the valve 78. From valve 78 the water passes through the flexible tube 79 into pipe 80 and from thence is discharged into tank 44. The amount of water and the air supplied are proportioned to 15 cause the passageway of practically all of the water from tank 43 to tank 44 while pipe 3 is discharging, so that at substantially at the completion of the discharging of pipe 3 tank 44 will overbalance tank 73 20 and weight 68. As soon as the bar 67 has passed the horizontal line in its swinging movement the weight 68 will immediately slide over to the opposite side and strike against plate 66 so as to give an additional 25 quick movement to the walking beam 47 and associated parts and thereby give a quick finishing turn or movement to the valve member 37 so as to fully turn the 30 same to its new position. In its new position the air will pass into pipe 6 and also the auxiliary by-pass or pipe 81, while the air from pipe 32 and the auxiliary pipe or by-pass 71 will exhaust as heretofore described. As the air passes downwardly 35 through pipe 6 for operating as heretofore described, air will also pass through the by-pass 81 to the valve 82 and from thence through the flexible hose 83 to the inlet pipe 84 which is formed similar to pipe 74 and 40 is provided with the same form of discharge head. This feeding of air into the tank or bucket 44 will of course cause the water to be returned to the bucket or tank 43 by 45 the path heretofore described, and when the 50 return of the water has been completed or substantially completed the weight 68 will again move longitudinally of the bar 67 for assisting in turning the valve. From this it will be observed that the cable or 55 rope 61 is pulled back and forth so as to move the valve back and forth.

Suitable guiding pulleys 85 and 86 are provided for guiding the rope in its movement, said guiding pulleys being supported 60 by suitable standards 87 and 88 connected in any suitable way to the casing 34. A pair of bumpers 89 and 90 are provided for limiting the swinging movement of the lever 63 and for cushioning the blow when 65 stopping.

As shown in Fig. 1, a screw 91 is provided which rests against the stem 64 of valve 37 for holding the valve against its seat, said screw being carried by a bracket 92 and forming part of the casing 34. The 70 buckets or tanks 43 and 44 may be supplied with water, oil or any other liquid as may be desired through suitable inlet members 93 and 94 and may be drawn at any time through valves 95 and 96. The passageways 40 and 41 preferably merge into an exhaust elbow 97 shown particularly in Fig. 1, which elbow may extend to any suitable discharge point as may be desired.

What I claim is:—

1. In a pump, a plurality of partially submerged tubular members, air operated means in each of said tubular members for controlling the flow of water therefrom, an oscillating valve for controlling the air admitted to said tubular members, a pair of feed pipes for driving air from said valve into said tubular members for alternately supplying and exhausting the air, and means for moving said valve so that compressed air will be alternately supplied to said air pipes and alternately exhausted therefrom, said means comprising a pivotally mounted beam, a member for connecting the opposite ends of said beam to said valve so that when the beam is moved to one position the valve will be turned to a corresponding position and when the beam is moved to the other position the valve will be turned to its opposite position, a pair of buckets pivotally connected to said beam, tubular members connecting said buckets so that the contents of one bucket may pass into the opposite bucket, a by-pass connected to said buckets and to the first mentioned air pipes whereby when the first mentioned air pipes are being exhausted a corresponding bucket will be exhausted and when the air pipe contains air under pressure some of the air will move into one of the buckets for forcing the liquid therein into the other bucket for overbalancing the lever and thereby turning the valve.

2. In a pump of the character described, a pair of tubular members having the lower ends submerged in water, part of said lower ends being perforated for allowing the water to enter the members, an upwardly opening check valve arranged in each of the tubular members above the apertures therein, a discharge outlet member arranged above said valve, a division member arranged above each of said discharge outlet members, each of said division members having a passageway therethrough, a plurality of uprights connected with said division members and acting as a guide, a float arranged within said guide, said float being formed with a packing on the lower end adapted to rest against said division member and

closing the passageway therein after a predetermined amount of water has been forced from the tubular members, upwardly opening check valves in the discharge members 5 for preventing the return of the water passed therethrough, and means for alternately supplying and exhausting compressed air in the upper part of each of the tubular members.

10 3. In a pump of the character described, water elevating means, a valve for supplying at different times compressed air to said means, a mechanism for swinging said valve from one position to another, said 15 mechanism comprising a walking beam, means for connecting the walking beam with the valve so that the valve will be turned upon each movement of the walking beam, a bucket pivotally connected to each end 20 of said walking beam, a liquid weight arranged in one of said buckets, a pipe connecting said buckets together so that said liquid may be forced from one bucket to the other so as to overbalance said walking 25 beam and thereby shift said valve, and means connecting the outlet ports of said valve with said buckets so that the lower bucket may receive air under pressure for forcing the liquid into the other bucket, 30 and a sliding weight associated with the walking beam for assisting said buckets by giving a quick turning movement to the walking beam after the same has reached a substantially horizontal position.

35 4. In a pump of the character described, a pumping mechanism adapted to be partially submerged in water, a valve for directing air to said pumping mechanism for operating the same, a pair of pipes for 40 leading the air from the valve to the pumping mechanism, said valve when in one position supplying compressed air to one of the pipes and exhausting the other, when in the opposite position, the operation being 45 reversed, and means for moving said valve from one position to the other, said means comprising a walking beam, flexible means connecting said walking beam with the valve so that when the walking beam is 50 moved from one extreme position to the other the valve will be correspondingly moved, a closed bucket or container pivotally mounted at each end of said walking beam, one of said buckets being adapted

to contain a predetermined quantity of liquid, means defining a by-pass for each of the buckets extending from the air supply pipes to the pumping mechanism to the respective buckets so that the bucket containing the liquid will be supplied with air 55 under pressure simultaneously with part of the pumping mechanism and thereby cause the empty bucket to become filled and overbalance the walking beam which automatically reverses the valve and thereby the 60 air supply to all parts of the device so that the action is repeated.

5. In a pump of the character described, a pumping mechanism arranged to be partially submerged, a pair of air pipes leading to said mechanism, a valve for alternately supplying and exhausting said air pipes whereby the pumping mechanism will operate alternately, and means for moving said valve from one position to the other 75 for causing an alternate supply of air to be turned on to said pipes, said means comprising a pivotally mounted walking beam, a member connecting the ends of said walking beam with the valve so that when the walking beam is moved from one extreme position to the other the valve will be likewise moved, a container pivotally mounted at each end of said walking beam, one of said containers being adapted to contain a pre- 80 determined quantity of liquid, means defining a by-pass from said air pipes to said containers, there being an independent by-pass for each container, the respective by-passes communicating with different air 85 pipes whereby the containers are supplied with air and exhausted simultaneously with the air pipes, and means providing a communication between the containers for directing the water from one container to the 90 other when air is forced into the container carrying the liquid, thus causing the containers to alternately overbalance the walking beam and thereby automatically shift at 95 predetermined intervals the valve from one 100 position to the other.

In testimony whereof I have signed my name to this specification in the presence of two subscribing witnesses.

GEORGE DORFFEL.
